UNITED STATES PATENT OFFICE.

JOHN E. HUTZEN, OF CHICAGO, ILLINOIS.

ROLL-REDUCING MACHINE.

1,196,241.

Specification of Letters Patent. Patented Aug. 29, 1916.

Application filed September 15, 1910. Serial No. 582,265.

To all whom it may concern:

Be it known that I, JOHN E. HUTZEN, a citizen of the United States, and resident of Chicago, in the county of Cook and State of Illinois, have made a certain new and useful Invention in Roll-Reducing Machines; and I declare the following to be a full, clear, and exact description of the same, such as will enable others skilled in the art to which it appertains to make and use the invention, reference being had to the accompanying drawings, and to letters or figures of reference marked thereon, which form a part of this specification.

Figure 1 is a side view of the machine. Fig. 2 is a horizontal sectional view. Fig. 3 is a vertical longitudinal section. Fig. 4 is a horizontal section of the reducing roll. Fig. 5 is a detail sectional view on the line 5—5, Fig. 1.

This invention has relation to roll machines designed chiefly for reducing cereals to filament form, and it consists in the novel construction and combinations of parts, as hereinafter set forth.

In the machine described, the channelled cutting rolls consist of removable thin cylinder-edged disks of larger and smaller diameter, compressed solidly together on their shafts from eye to perimeter by means of suitable bracing collars, such rolls working together so that each set of rolls gives off two sets of filaments, the material being prepared by the action of crushing rolls over the disk rolls. Each disk-roll is easily taken apart for repair, and when the disks are assembled on the roll shaft, they are designed to be solidly held together, and especially at their peripheral portions, because of their thin character. The adjustment of the rolls toward and from each other is of positive character in either direction, and is so designed that after the adjustment as to the thickness of the filament, this size will be maintained evenly throughout its length.

In the accompanying drawings, illustrating the invention, the letter *a* designates a hopper, in or below which is placed a pair of smooth steel feeding and crushing rolls *b*, *b*, designed to crush the grain, after it has been put in proper condition for shredding, by boiling or soaking. Scrapers *c*, are

placed below and in engagement with the surfaces of rolls *b*, *b*, to direct the crushed material between the grooved or channeled cutting rolls below these feed rolls.

d, represents framework, which is provided with bearings for the boxes *e*, *e*, of the cutting rolls, and with such other bearings as may be required for the necessary parts of the mechanism.

g, *g*, designate parallel steel shafts, which are the basis of the cutting rolls *f*, *f*; and on these shafts are seated the roll bodies composed of annular steel disks *h*, and *k*, arranged in series in the following manner. The disks are circular, and are made of thin sheet steel, saw steel being easily available for the purpose. The thickness of steel preferred is about one thirty-second of an inch. The disks are bored to provide proper openings whereby they are seated on the shaft, and the openings may be provided with seats for placing a key or feather to prevent their turning on the shaft. The disks employed are designed to be of two diameters, the smaller disks *k*, being about five inches in diameter, and the larger disks *h*, about five and one-eighth inches; the difference between the diameters being about one-eighth of an inch more or less. These disks are arranged in an alternative manner on the shaft, so that a small disk is seated between two large disks, and its circumferential edge forms the bottom of a small channel whereof the parallel circumferential portions of the larger disks form the side walls, and the terminal rectangular cutting edges of which, because of the hardened character of the disk surface, are designed to serve an excellent purpose. Such channel is therefore circumferential, having a depth of about a sixteenth of an inch, more or less, and a width of about a thirty-second of an inch, more or less. The cutting disks and the fine channels between their circumferences are designed to operate upon the grain fed to the rolls in such manner as to reduce the same to fine filaments of continuous length, by a cutting action which materially facilitates the work, and lessens the power required therein. As the cutting disks are thin and their circumferential channels narrow, the cutting rolls sometimes fail to take the small kernels of grain, so that the

100
105

feed may be irregular and produce uneven filaments. The rolls b , b , above the cutting rolls are designed to crush or mash the kernels a little to modify their smoothness 5 and obviate this difficulty.

The series of large and small disks is held on the shaft of the roll by means of collars m , and n , one or both of which should be screw-threaded in its central opening to engage a thread of the shaft. In this way the collar may be turned to compress the series of disks closely together in as nearly a solid condition as possible. One of these collars should correspond with the larger 10 disks in diameter, while the other has the diameter of the smaller disk. In this way the marginal portions of the disks are held firmly together and spreading is prevented.

The shafts of the cutting rolls are seated 20 in bearings; and one of said shafts in bearings z , z , in boxes e , e , which are made positively adjustable in order that one of the rolls may be accurately adjusted so that the cylindroform edges of its cutting disks will 25 meet or intermesh between the edges of the cutting disks of the opposite roll in order to have cutting action on the softened grain, whereby it is cut and drawn into the fine circumferential channels of the rolls in their 30 rotation, from which the product is discharged by the teeth t , in the form of continuous filaments or threads of such thickness as is determined by the adjustment of the rolls, upon a receiver or carrier belt p , below. In order to prevent undue friction between the cutting edges of the cutting disks where they are designed to intermesh, thin 35 paper disks may be interposed between the large and small disks of the series.

40 The shafts g , g , of the cutting rolls are provided with gear wheels s , s , which engage each other, and power may be used to transmit motion to one of these gear wheels. Or, for a hand machine, a crank may be applied to one of the shafts.

The toothed scraper or comb device j , consists of a frame carrying a series of flat-side bar teeth t , having between each two teeth separating strips v , which are preferably 50 flanged at each end downward to provide a stop lug 2 , these teeth and strips being of the same depth so that their upper and lower edge surfaces are flush with each other. The frame or stock of the comb is 55 rectangular, having upper and lower plates or bars 3 , between which the teeth and strips are seated, the latter engaging the edges of the lower plate by their lugs 2 . The stock is provided with side bars 4 , having journals 60 seated in bearings 6 , of the frame. The outer ends of the teeth t , abut against a spring bar 7 , which is supported by a back bar $7'$. The springs are shown at 8.

65 Thumb screws 9 , passing through side bars of the head or stock, engage the outer

teeth of the comb, and when adjusted and tightened up hold the teeth securely and in proper position, so that the ends of the teeth enter the channels of the rolls between the larger disks, in such wise as to bear 70 against the bottoms of the channels, under the spring pressure, sufficiently to discharge the filling of the channels in the form of flat or parallel sided filaments as above indicated. The working ends of the teeth t , which engage the edges of the smaller disks of the roll, are designed to have a concave curvature corresponding to that of the disk circumference. The concave end of each tooth therefore terminates in an acute edge 80 of nearly the width of the channel, and is designed to do efficient work in the discharge of the filament of material therefrom.

In order to provide for exact adjustment 85 of the cutting rolls, each journal bearing box e , is provided with a boss e' , which is provided with a threaded aperture to engage the end of an adjusting screw a' , which is seated in a bearing in the frame, and is 90 held from endwise movement by means of removable collars b' . The bearings z , z , are also made vertically adjustable by means of bearing screws c' , c' . By means of this vertical adjustment of the bearings which engage the movable roll, this roll is designed to be brought into exact axial parallel relation with the coacting roll, so that the edges of the cutting disks of opposite rolls will not 95 grind upon each other along their line of 100 operation. This exact alinement is of the first importance, because of the fineness or smallness of the elements of the rolls, which requires elimination of angular variation, so that the edges of all the larger disks shall 105 exactly meet along the rolls, and in this way divide the cereal into filaments by such meeting without intermeshing. Angular variation in the alinement of the rolls will prevent clean separation of the cereal material, 110 and cause webs to be left in the work, thereby defeating the purposes in view.

The boxes e , being positively connected to the adjusting screws a' , by the threading of their apertures, the cutting roll carried by 11 the bearings z is easily adjusted toward or from the coacting cutting roll which is in fixed bearings, and is held to its adjustment. This adjustment is therefore positive, and is necessary in this fine work, because the 120 slender filaments have not sufficient body to effect of themselves an outward or separating movement of the rolls. The degree of adjustment is easily noted by means of indicators fixed over the collars b' , which may 125 be graduated or marked on their faces. By this means the equality of adjustment of the two boxes, which is necessary on account of the threadlike nature of the product, is also readily secured.

Having thus described my invention, what I claim as new and desire to secure by Letters Patent is:

1. In a reducing roll machine, a roll having parallel-wall circumferential channels, a similar roll parallel to and coacting with the first roll, a series of independently movable discharging scrapers engaging the channels of each roll, fixed separating strips between each two scrapers, and a pressure spring device abutting the series of discharging scrapers, said spring device serving to keep the scrapers in engagement with the rolls.
2. In a reducing roll machine, a roll having a series of fine circumferential channels, a similar roll parallel to and coacting with the first roll and having circumferential

channels of the same size therewith, bearing boxes for the journals of the first roll, adjusting means connected to said boxes for moving said first roll in a right line toward or from the coacting roll, and means for vertical right line adjustment of the bearings at each end of the roll for rectifying angular variation of contact along the line of operation of the channeled surfaces of the rolls.

In testimony whereof I affix my signature, in presence of two witnesses.

JOHN E. HUTZEN.
